US0D1052401S

(12) **United States Design Patent** (10) **Patent No.:** **US D1,052,401 S**
(45) **Date of Patent:** **** Nov. 26, 2024**

(54) **PACKAGING BAG**

(71) Applicant: **Guangzhou Yanmei Biotechnology Co., Ltd**, Guangdong (CN)

(72) Inventor: **Jianyong Gao**, Guangdong (CN)

(73) Assignee: **Guangzhou Yanmei Biotechnology Co., Ltd**, Guangdong (CN)

(**) Term: **15 Years**

(21) Appl. No.: **29/946,710**

(22) Filed: **Jun. 11, 2024**

(51) LOC (14) Cl. **09-07**

(52) U.S. Cl.

USPC **D9/456**

(58) **Field of Classification Search**

USPC D9/414, 416, 418, 419, 421, 423, 424, D9/428, 430, 431, 432, 437, 456, 553, D9/559, 566, 696, 702, 707, 731, 732, D9/737, 740, 744, 745, 756; D7/538, D7/541, 546, 549, 553.6, 553.3, 557, 586, D7/601, 602, 628; D3/203.3, 309, 310, D3/311, 312, 313
